William F. Sprengnether, deceased

Application June 12, 1951, Serial No. 15,513

Term of patent 14 years

(Cl. D52—1)

To all whom it may concern:

Be it known that I, William F. Sprengnether, Jr., a citizen of the United States of America, residing in the city of St. Louis, State of Missouri, have invented a new, original, and ornamental Design for a Builder's Transit Level, of which the following is a specification, reference being had to the accompanying drawing, forming a part thereof.

Fig. 1 is a perspective view of a builder's transit level, showing my new design, and Figs. 2, 3, and 4 are, respectively, an end view, a top plan view, and a side elevation of the builder's transit level shown in Fig. 1, Fig. 4 illustrating the side opposite to the side illustrated in Fig. 1.

I claim:

The ornamental design for a builder's transit level, as shown.

WILLIAM F. SPRENGNETH, JR.
